(57) **CLAIM**

The ornamental design for a support bracket, as shown and described.

DESCRIPTION

FIG. 1 is a front-top-right perspective view of a support bracket according to the present invention.

FIG. 2 is a front view of the support bracket.

FIG. 3 is a rear view of the support bracket.

FIG. 4 is a top view of the support bracket.

FIG. 5 is a bottom view of the support bracket.

FIG. 6 is a right side view of the support bracket.

FIG. 7 is a left side view of the support bracket; and,

FIG. 8 is a rear-bottom-right perspective view of the support bracket.

The broken lines in the drawings illustrate portions of the support bracket that form no part of the claimed design.
